UNITED STATES PATENT OFFICE.

LOUIS J. BISHOP, OF CLEVELAND, OHIO.

CASH-CARRIER.

SPECIFICATION forming part of Letters Patent No. 380,979, dated April 10, 1888.

Application filed November 26, 1887. Serial No. 256,260. (No model.)

To all whom it may concern:

Be it known that I, LOUIS J. BISHOP, of Cleveland, in the county of Cuyahoga and State of Ohio, have invented a new and useful Improvement in Cash-Carriers, of which the following is a specification.

The object of my invention is to provide a simple and efficient cash-carrier for store-service; and it consists in the peculiar construction and arrangement of devices for propelling the carrier, and also in the peculiar construction of the carrier arranged to run upon a track-wire, as will be hereinafter fully described.

15 Figure 1 is a side elevation with a part of the length of pillar B broken away. Fig. 2 is a plan view with the pillar B in section, and Fig. 3 is a vertical sectional view through the axis of the propelling-arms.

20 In the drawings, B represents a pendent support attached to the ceiling and extending to convenient reach in the store. This support is made of a metal pipe or hollow pillar, and to its lower end is attached the track-wire W, which extends to the cashier's desk, and upon which is arranged the cash-carrier I. To the bottom of this pillar B is screwed a horizontal plate, p, which is connected to another parallel plate, p', below it by means 25 of three bolts, o o'. The two outside bolts, o o, are padded with a covering composed of rubber tubing, while the middle bolt, o', forms an axis upon which are fulcrumed two curved propelling-arms, A' A². These propelling-arms have their convex surfaces next to the carrier, and open and close like the blades of a pair of shears. Their real function, however, is that of wiper-cams, which, when they close together upon the carrier, act thereupon 30 to force the carrier over the wire, the carrier receiving therefrom an impulse which projects it along the track-wire to its destination. The carrier I is, as usual, suspended upon the track-wire by means of wheels, and at its four 35 corners are arranged vertical rollers J at the points where the propelling-arms or wiper-cams bear against it. These rollers reduce the friction, and make the carrier to yield to the pressure of the propelling-arms in a manner more sensitively responsive.

The propelling-arms in closing upon the carrier bear equally and simultaneously upon

opposite sides of the carrier, so that the carrier does not rock about its point of suspension.

55 The propelling-arms are normally held open or apart from each other by means of spiral springs s s', attached at one end to the arms and at the other end to the axial bolt or one of the plates p p', and a washer, t, placed between the arms on the axial bolt, serves to reduce friction and prevent them from grinding against each other.

In order to operate the propelling-arms, a horizontal frame, L, is connected by brace-rods M to the lower end of pillar B, and is provided with four pulleys, 1 2 3 4, of which the outer ones, 1 and 4, are arranged in a horizontal plane and the inner ones, 2 and 3, in a vertical plane. H is a pull-cord with a 60 suitable tassel or handle, which cord extends up to the frame L and is connected to two other cords, F and G, which pass first over the pulleys 2 and 3, and then around pulleys 1 and 4, and thence pass to and are attached to 65 the rear ends of the propelling-arms. Now, when the pull-cord is drawn quickly down, it will be seen that the propelling-arms, 70 impinging upon opposite sides of the carrier, force it impulsively on to its destination. 75 After the carrier has thus been dispatched the springs s s' restore the propelling-arms and the padded bolts o o act as stops to limit their backward movement. The cash-box of the carrier I consists of a cylinder, i, 80 attached to the under side of the carrier in pendent relation, and having hooks h on its outer surface, combined with another telescopic cylinder, j, which slides into i, and has also hooks k, that are locked into h by a rotary 85 motion to connect the two cylinders. A bayonet-joint may be used, however, to connect these two cylinders in substantially the same way.

To receive and hold the cash-carrier at the 90 end of its route, a spring-clasp, K, is attached to the pillar B, which clasp also forms an elastic buffer to receive the impact of the carrier.

Having thus described my invention, what I claim as new is—

1. A propelling device for a cash-carrier, consisting of the combination of two curved-face levers disposed with their convex sides

facing each other, the said levers being fulcrumed to operate in opposite directions upon the carrier with a cam action, as described.

2. The combination, with the track-wire and the cash-carrier mounted thereon and having friction-rollers J at its ends, of the curved-face propelling-arms fulcrumed to operate in opposite directions on the friction-rollers with a wiper-cam action, as described.

3. The combination, with the propelling-

arms A' A², of the pillar B, with plates p p' and bolts o o', the springs s s', pulleys 1 2 3 4, and pull-cords F, G, and H, attached to the propelling-arms, substantially as and for the purpose described.

LOUIS J. BISHOP.
